UNITED STATES PATENT OFFICE.

ARTHUR TREVOR DAWSON AND GEORGE THOMAS BUCKHAM, OF WESTMINSTER,
LONDON, ENGLAND, ASSIGNEES TO VICKERS LIMITED, OF WESTMINSTER, LON-
DON.

FIRING MECHANISM OF ORDNANCE.

1,360,731.

Specification of Letters Patent. Patented Nov. 30, 1920.

Application filed November 13, 1917. Serial No. 201,846.

To all whom it may concern:

Be it known that we, Sir ARTHUR TREVOR DAWSON, knight, and Sir GEORGE THOMAS BUCKHAM, knight, both subjects of the King of Great Britain, residing at Vickers House, Broadway, Westminster, in the county of London, England, have invented certain new and useful Improvements in or Relating to the Firing Mechanism of Ordnance, 10 of which the following is a specification.

This invention relates to the firing mechanism of guns of the so-called non-recoil type in which the barrel is open at each end and receives in addition to the projectile and the powder charge a compensating mass which when the gun is fired is ejected from the rear end of the barrel, the inertia of this mass being substantially equal to that of the projectile so that the recoil force due to the firing of the projectile is more or less neutralized. In such guns it has been proposed to construct the barrel in two portions, viz. a forward portion (herein termed the fixed portion) and a rear portion (herein termed the movable portion) connected together by interrupted threads or collars, the movable portion after it has been unlocked from the fixed portion being capable of displacement to enable the gun to be loaded.

According to the present invention the firing mechanism in a gun of the above type comprises a spring controlled striker or firing pin and means, operated by the device for unlocking the movable barrel portion, for retracting the striker before any unlocking movement of the said barrel portion occurs; the said means also serve to cock the striker during the movement of the barrel portion toward its open or loading position. The above described arrangement provides adequate safety against premature firing and insures an easy operation during the compression of the striker spring while leaving sufficient reserve force for effecting the extraction of the cartridge case. The striker is released to fire the gun by a trigger which is mounted on the hand grip portion of a training arm on the fixed barrel portion and operates upon the sear through a system of rods and levers.

In order that the said invention may be clearly understood and readily carried into effect, we will describe the same more fully

with reference to the accompanying drawings, in which:—

Figure 1 is a side elevation showing part of a gun of the kind referred to provided with a constructional form of our improvements.

Fig. 2 is a section taken approximately on the line 2, 2 of Fig. 1 viewed from the left.

Fig. 3 is a plan of Fig. 2 with the right hand portion thereof in section on the line 3, 3 of Fig. 2 and

Fig. 4 is a local section on the line 4, 4 of Fig. 1.

A is the fixed barrel portion and B is the movable barrel portion connected together by interrupted threads or collars. In the example shown the means for displacing the movable barrel portion B are similar to the means set forth in the specification of our United States patent application No. 201,845 and comprise a sleeve C rotatably mounted upon a spindle B' and actuated through bevel gearing by a hand lever B*. This sleeve carries a horizontally arranged roller pin C² (Fig. 1) engaging with a recess b² (see Fig. 4) in a cam band B² attached to the movable barrel portion B, this roller pin serving to angularly displace the movable barrel portion about its axis to unlock it from the fixed barrel portion. The said sleeve also carries a radially arranged roller pin (not shown) for engaging with a cam groove in the cam band B² to displace the movable barrel portion rearward and rock it about the axis of the spindle B' after the said unlocking operation has been performed.

D is the striker which is disposed transversely to the axis of the gun within a casing D' connected to a band D'' secured to the fixed barrel portion and which passes through a hole in the wall of this barrel portion. D² is the striker spring which is situated within the casing D'. The means for retracting and cocking the striker comprise a cam groove E formed in the sleeve C, with which groove engages a ball pin E' on the rear end of a longitudinally sliding rod E². The other end of this rod is connected to one arm of a bell crank lever E³ pivoted to a bracket A⁴. This bracket has a lug A⁵ connected to an elevating arc A⁶ attached to the fixed barrel portion A. The other arm of this bell crank lever has a hole

through which passes a rod e terminating at its lower end in an inverted T the arms of which are engaged by the said arm of the bell crank lever E^3 . This rod e is adjustably connected by screw threads to a second rod e' which in turn is connected to a cocking lever e^2 pivoted at e^3 to lugs on the striker casing D' and provided with arms e^4 , e^4 which engage with lateral pins or projections d , d on a member D^x attached to the striker. The cocking lever e^2 has a handle e^x for enabling the striker to be recocked. Loosely surrounding the rod and arranged in contact with the upper surface of the last mentioned arm of the bell crank lever, is a washer e^0 between which and an enlarged portion at the lower end of the rod e' a spring e^5 is disposed. The re-cocking movement of the lever e^2 takes place independently of the bell crank lever E^3 owing to the loose connection between the rod e and the bell crank lever. The said re-cocking movement compresses the spring e^5 and this spring returns the cocking lever, when released, to its normal position so as not to interfere with the throw of the striker.

When the movable barrel portion is fully locked the roller pin C^2 occupies in relation to the recess b^2 , the position shown by Fig. 30 4, the ball pin E' at this time engaging with a steep portion of the cam groove E . Thus when movement in the direction of the arrow in Fig. 4 is given to the sleeve C , the striker is retracted by the said steep portion 35 of the cam groove E before the roller pin C^2 comes into contact with the left hand wall of the recess b^2 , that is to say before any unlocking movement is imparted to the movable barrel portion. Continued movement 40 of the sleeve C in the same direction then unlocks the movable barrel portion from the fixed barrel portion during which time the cam groove E effects the cocking of the striker D' as follows: The cam groove causes the rod E^2 to move rearward, thereby lifting the striker through the medium of the bell crank lever E^3 , the rods e , e' , the lever e^2 , the arms e^4 , e^4 , the pins d , d and the member D^x , until the striker reaches 45 a position in which the nose of a sear f^5 hereinafter referred to can engage with the under side of the member D^x , the said sear being displaced to its engaging position by a bent spring f^5x .

50 F is the aforesaid training arm (so termed because the gunner, by pushing or pulling on it, trains the gun) which is carried by a socket F' in the trunnion arm on the band D^x secured to the fixed barrel portion A and 55 f is the trigger pivoted on the hand grip

portion of the said training arm. This trigger engages with a sliding pin or rod f' which is arranged axially within the arm F. The inner end of this sliding pin operates upon a bell crank lever f^2 connected to an upright rod f^3 whose lower part passes through a transverse hole in the socket F' and whose upper end is connected to a lateral arm f^4 on the sear f^5 . The aforesaid striker casing D' carries a detachable cover d^x for the sear, this cover being dovetailed into the casing and being retained in place by the sear spring or by a split pin.

What we claim and desire to secure by Letters Patent of the United States is:—

1. In firing mechanism for non-recoil ordnance, having a fixed barrel-portion and a movable barrel-portion, the combination with a device for unlocking the movable barrel-portion, of a spring controlled striker and means, operated by said device, for retracting the striker before any unlocking movement of said movable barrel-portion occurs.

2. In firing mechanism for non-recoil ordnance, having a fixed barrel-portion and a movable barrel-portion, the combination with a device for unlocking the movable barrel-portion, of a spring controlled striker and means, operated by said device, for retracting the striker before any unlocking movement of said movable barrel-portion occurs and for cocking the striker during the movement of the movable barrel-portion toward the open or loading position.

3. In firing mechanism for non-recoil ordnance, having a fixed barrel-portion and a movable barrel-portion, the combination of the striker and a rotary member having a cam groove for retracting the striker, and a device operated by said rotary member for unlocking the movable barrel-portion, said groove retracting the striker before any unlocking movement of the movable barrel-portion occurs.

4. In firing mechanism for non-recoil ordnance, having a fixed barrel-portion and a movable barrel-portion, the combination of the striker and a rotary sleeve having a cam groove for retracting the striker, and a device operated by said rotary sleeve for unlocking the movable barrel-portion, said groove retracting the striker before any unlocking movement of the movable barrel-portion occurs.

In testimony whereof we affix our signatures.

ARTHUR TREVOR DAWSON,
GEORGE THOMAS BUCKHAM.
